UNITED STATES PATENT OFFICE.

NANETTE S. EMERSON-FRENCH, OF NEW YORK, N. Y.

IMPROVEMENT IN TOILET-MASKS.

Specification forming part of Letters Patent No. **194,815**, dated September 4, 1877; application filed May 28, 1877.

To all whom it may concern:

Be it known that I, NANETTE S. EMERSON-FRENCH, of the city, county, and State of New York, have invented a new and Improved Toilet-Mask, of which the following is a specification:

In the accompanying drawings, Figure 1 represents a perspective view, and Fig. 2 a cross-section of my improved mask.

Similar letters of reference indicate corresponding parts.

The object of this invention is to furnish, for the purpose of beautifying the complexion, removing moth, tan, and sunburn, curing eruptions and inflammation of the skin, and softening and healing the skin, an improved toilet-mask, that fits neatly and yieldingly to the face, and forms a protection for the same against external influences.

The invention consists of a toilet-mask formed of an outer layer of suitable pliable fabric, and an inner layer of heating or medicated fabric.

In the drawing, A represents the outer layer of my improved mask, made of any pliable fabric, such as cotton, linen, silk, kid, leather, rubber, &c., and B the inner layer, which is of flannel or similar soft and fine material.

When it is desired to prepare the mask with cooling substances, such as glycerine or other medicated lotions, an additional layer of linen or other material may be used, according to the special purpose for which the skin is to be treated.

The toilet-mask is to be worn at night, not being annoying on account of its pliability, and exerting a quickly-healing and softening influence upon the pores of the skin, so as to remove impurities and beautify the complexion, and form, furthermore, a protection against the influence of the sun and the bites of insects in summer, and against cold winds, chapping, and frost-bite in winter.

Having thus described my invention, I claim as new and desire to secure by Letters Patent—

As a new article of manufacture, a toilet-mask composed of an outer layer of pliable fabric, and an inner layer or lining of flannel or similar soft material, substantially as described and shown, for the purpose set forth.

NANETTE S. EMERSON-FRENCH.
